UNITED STATES PATENT OFFICE

119,966

DESIGN FOR A SPRING SCALE

Abraham J. Shekter, Jamaica, N. Y.

Application January 26, 1940, Serial No. 89,736

Term of patent 7 years

To all whom it may concern:

Be it known that I, Abraham J. Shekter, a citizen of the United States, residing at Jamaica, in the county of Queens and State of New York, post-office address Nos. 87-78 150th Street, corner of 88th Avenue in said city, have invented a new, original, and ornamental Design for Spring Scales, of which the following is a specification, reference being had to the accompanying drawing, forming part thereof.

Fig. 1 is a front view of a spring scale showing my new design.

Fig. 2 is a side view of the same.

I claim:

The ornamental design for a spring scale, as shown.

ABRAHAM J. SHEKTER.
